US0D1010975S

(12) **United States Design Patent** (10) **Patent No.:** **US D1,010,975 S**
(45) **Date of Patent:** **** Jan. 16, 2024**

(54) **SHAPEWEAR JUMPSUIT**

(71) Applicant: **Guangzhou Melody Clothing Co., Ltd.**, Guangzhou (CN)

(72) Inventor: **Xiaodan Liu**, Shantou (CN)

(73) Assignee: **Guangzhou Melody Clothing Co., Ltd.**, Guangzhou (CN)

(**) Term: **15 Years**

(21) Appl. No.: **29/909,502**

(22) Filed: **Aug. 7, 2023**

(30) **Foreign Application Priority Data**

May 29, 2023 (CN) 202330322317.7

(57) **CLAIM**

The ornamental design for a shapewear jumpsuit, as shown and described.

DESCRIPTION

FIG. 1 is a front perspective view of a shapewear jumpsuit, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the shapewear jumpsuit, which form no part of the claimed design.

1 Claim, 8 Drawing Sheets
